UNITED STATES PATENT OFFICE.

CARL GABRIELSON, OF SYRACUSE, NEW YORK.

PLATEN-CLUTCH FOR TYPEWRITING-MACHINES.

1,393,277.

Specification of Letters Patent. Patented Oct. 11, 1921.

Application filed February 5, 1919. Serial No. 275,175.

To all whom it may concern:

Be it known that I, CARL GABRIELSON, a citizen of the United States, and residing at Syracuse, county of Onondaga, State of New York, have invented certain new and useful Improvements in Platen-Clutches for Typewriting-Machines, of which the following is a specification.

This invention relates to that type of clutch which normally locks the line space ratchet wheel to a typewriter platen, but which permits the platen to be released so that it may be turned while the ratchet wheel is stationary for irregular spacing and other purposes. The invention is illustrated in the accompanying drawings in which:—

Figure 1 is a central longitudinal sectional view of a platen in which the invention is embodied;

Fig. 2 is an enlarged section of one end of the platen in a plane at right angles to the plane of section of Fig. 1. Fig. 2 illustrates the position of the parts with the ratchet wheel locked to the platen;

Fig. 3 is a view similar to Fig. 2 but showing the position of the parts when the platen is free from the ratchet wheel;

Fig. 4 is an end view of the platen with one of the heads removed to show the clutch mechanism, the shaft being shown in section;

Fig. 5 is a detail of means for holding the clutching mechanism in the released position;

Fig. 6 is a section on the line 6—6 of Fig. 5; and

Fig. 7 is a perspective view of the rocking member of the clutch mechanism.

Referring to the drawings 10 indicates the wooden core of a typewriter platen, 11 the hard rubber sleeve surrounding the core, 12 the left head of the platen which is suitably attached to the wooden core and 13 the left knob for turning the platen which is mounted on a short shaft fixed in the head 12. These parts are of ordinary construction, excepting that the wooden core is bored out in a peculiar manner as will be presently described.

The platen 10 has a large bore or axial opening 14 at its right hand and a smaller bore 15 at its left end, thus providing an intermediate shoulder 16. At the right end of the platen there is attached a circular plate 17 having a hub 18 which fits the bore

14, the plate 17 being attached to the wooden core by screws or other securing means. The plate 17 has an annular shoulder 20 on its outer side on which is mounted a ring 21 bearing 21, on the surface of which runs a series of rollers 22. Mounted on the rollers is a ring 23 carrying a ratchet 24. This ratchet cooperates with the usual spring holding pawl or roller 25 and with a line 65 space feed pawl, not shown. On the outer side of the bearing 21 and the ring 23 there is a concentric cap 26. The ring 17, the bearing 21, and the cap 26 are rigidly connected together by means of suitable screws 27. 70 The rollers 22 fit the annular space between the bearing 21 and the ring 23. When these rollers are free the platen may be turned independently of the ratchet wheel by turning the platen shaft 28, which is rigidly fixed in 75 the head 26, or by turning the knob 13.

A rocking device for operating the clutch is shown in Fig. 7. The head 29 of this device is annular and the shaft 28 passes loosely through it. Radially extending from one side of the head 29 is a boss 30 which is pivotally mounted on a screw 31, mounted in the ring bearing 21, as shown in Figs. 1 and 4. Diametrically opposite the boss 30 is an arm 32 which is flattened on two sides, 85 thus providing a substantially rectangular end 33 which lies between the adjacent rollers in the roller channel, as shown in Fig. 4. The rollers are loose in the channel and the clutch disengaged when the rectangular end 90 33 of the arm 32 has its flat sides parallel with the rollers. When this rocking device is turned on its axis about the screw 31 the squared end 33 presses the rollers apart and takes up all slack in the raceway, thus clamping the ratchet wheel to the race ring, which is rigidly connected to the platen. Under these circumstances, the platen must turn with the ratchet wheel. To normally hold the parts in this position, I provide the arms 95 34 on the rocker (Figs. 1, 2 and 7). The free ends of these arms engage cam surfaces 35 on opposite sides of a cam block 36 mounted on the shaft 28 within the platen. The cam block is normally pressed to the 100 right by a spring 37 surrounding the shaft 28 and abutting against the nut or shoulder 38. At the other end the spring bears on the cam block forcing it to the right and holding the arms in the position shown in Fig. 2 in 110 which position the rectangular end 33 is turned so as to crowd the rollers in their

raceway to lock the ratchet ring to the platen. The head of the screw 31 is also preferably located in the roller raceway and forms an abutment against which the rollers are crowded.

To release the platen from the ratchet wheel the cam block 36 is moved to the left against the pressure of the spring 37, permitting the arm 34 to drop or move into the 10 position shown in Fig. 3. This is accomplished by means of a rod 39, one end of which engages a projection 40 on the cam block 36, while the other end extends out 15 into position to be engaged by a smaller knob 41 on the right end of the platen shaft. The rod 39 lies in a groove in one side of the platen shaft 28 and is slideable therein. The right end of the rod 39 normally projects beyond the right end of the platen shaft 28. 20 On the right end of the platen shaft there is mounted a sleeve 42 which, as shown, is integral with the knob 41. Upon this sleeve is mounted a second sleeve 43, upon which is fixed a twirling knob 44. The knob has 25 a limited movement on the shaft, longitudinally, but turns the shaft by means of pin 45 which is fixed on the shaft and extends through slots in the sleeves 42 and 43, as shown in Figs. 2 and 6. The pin and the 30 slot in the sleeve 43 are covered by means of a cylindrical projection 46 which is integral with the knob 41, as shown in Fig. 2. The sleeve 43 is retained lengthwise on the sleeve 42 by means of the nut 47 on one end and 35 the pin 45 at the other.

When it is desired to release the platen from the line space ratchet the knob 41 is pressed to the left into the position shown in Fig. 3. This presses the rod 39 to the 40 left and moves the cam block 36 compressing the spring 37. The arms 34 then assume the position shown in Fig. 3 and the rollers 22 are released and freed, as previously stated, permitting the platen to be turned 45 to any extent without turning the ratchet wheel. On releasing the knob 41 the spring 37 moves the cam block, rod 39, and knobs 41 and 44 to the right into normal position.

If it be desired to hold the parts in the 50 position shown in Fig. 3 with the platen free from the ratchet ring, this may be accomplished by turning the knob 41 so as to engage the pin 45 in the recess 48 cut in the inner sleeve 42. This will prevent the spring 37 from acting until the knob 41 is turned in the reverse direction.

What I claim and desire to secure by Letters Patent is:

1. The combination with a typewriter 60 platen and a ratchet ring thereon of rollers carried by the platen and on which said ring is mounted and means for crowding the rollers in their raceway to clamp the ring to the platen, said means comprising a part 65 extending into the race between the rollers

and means for turning said part to exert separating pressure on and crowd the rollers.

2. The combination with a typewriter platen of an annular race fixed on the platen, 70 rollers in said race a ratchet ring surrounding and running on said rollers and spring operated means for normally crowding the rollers in the race to lock the ratchet ring to the platen, said means comprising a part adapted to turn on an axis at right angles to 75 the axis of the platen and having a non-circular portion extending between the rollers.

3. In a typewriting machine the combination with a platen of a head fixed to said 80 platen and a shaft fixed in the head and centrally arranged in the platen, an annular race in the head, rollers in said race, a ratchet ring mounted on said rollers, means adapted to crowd the rollers to lock the ring 85 to the platen and a cam mounted on said shaft and spring operated to normally effect the locking of the ratchet ring to the platen.

4. In a typewriting machine the combination with a platen of a head fixed to the 90 platen, a shaft axially arranged in the platen and fixed to the head, a knob on said shaft for turning the platen, a ratchet ring mounted on the platen head, a cam device movably mounted on said shaft, a spring for 95 moving said cam in one direction and means for moving the cam in the opposite direction against the pressure of the spring, and a device operated by the cam under the pressure of the spring for locking the ratchet 100 ring to the platen.

5. In a typewriting machine the combination with a platen of a roller race fixed to the platen at one end thereof, rollers in said race, a ratchet ring mounted on said 105 rollers, a rocking device having its axis at right angles to the axis of the platen and having a non-circular projection extending into the race between the rollers, a spring normally tending to move the rocking device 110 into position to crowd the rollers and clamp the ring to the platen and a slideable knob for compressing the spring to release the ratchet ring from the platen, whereby the platen may be turned for irregular spacing. 115

6. In a typewriting machine the combination with a platen shaft and with a platen mounted thereon of a ratchet ring mounted on the platen with freedom for relative movement, a spring operated device mounted on 120 the shaft for normally clutching the ratchet ring to the platen, a knob slidably mounted on the end of the shaft, means for connecting the knob with the clutching device 125 whereby a longitudinal movement of the knob will unclutch the ratchet ring and means for locking the parts in position to hold the ratchet ring free whereby the platen may be turned independently thereof.

7. The combination with a typewriter 130

- platen of a head thereon having a roller race, rollers in said race, a ratchet ring mounted on said rollers and means for crowding the rollers to lock the ratchet ring to the platen, 5 said means including an abutment extending into the roller race at one point thereof and a device extending into the roller race at another point thereof and means for turning said device to crowd the rollers against the abutment and lock the ratchet ring to the platen.
8. In a typewriting machine the combination with a platen of a head fixed to said platen and a shaft fixed in the head and centrally arranged in the platen with a surrounding chamber, an annular race in the head, rollers in said race, a ratchet ring mounted on said rollers, means adapted to crowd the rollers to lock the ring to the 15 platen, a cam mounted on said shaft within the platen adapted to control said locking means, a spring for normally holding said
- cam in locking position, and means extending from said cam through said head and shaft for manually moving said cam to unlocked position. 25
9. In a typewriting machine the combination with a platen of a head fixed to said platen and a shaft fixed in the head and centrally arranged in the platen with a surrounding chamber, an annular race in the head, rollers in said race, a ratchet ring mounted on said rollers, means adapted to crowd the rollers to lock the ring to the 30 platen including a pivoted member having a pawl extending within the platen and a cam mounted on said shaft within the platen and spring operated to turn said pivoted member through said pawl to normally effect the locking of the ratchet ring to the 35 platen. 40

In testimony whereof I affix my signature.

CARL GABRIELSON.
